OVER AND UNDER ACTUATOR FOR
ELECTRIC SWITCHES

John S. Coldwell, Milwaukee, Wis., assignor to
Globe-Union Inc., Milwaukee, Wis., a corpora-
tion of Delaware

Application August 28, 1950, Serial No. 181,904

11 Claims. (Cl. 200—154)

1

This invention relates to improvements in electrical switches and particularly to such switches of the quick-make and quick-break type.

Switches of this type are frequently used in connection with other control components, such as radio rheostats and the like, and are operated by the same control member as such component. Heretofore such switches have been added as a complete unit to the other component with an associated mechanism to form the inter-operative connection. The combined unit so made is comparatively bulky and expensive and not easily used in such applications as miniature radio sets, hearing aids, and the like.

One object of this invention, therefore, is to provide a switch of this type which may be simply and inexpensively built into another control component to create a small compact unit.

Quick-make and quick-break actions have been accomplished by toggle mechanisms, hill and valley constructions, ball and detent mechanisms, garter springs, and other like devices. Each type is particularly adapted for a special application. Most of them are complicated and costly to make. Some of them do not have true snap action, slow operation of the control member eliminating the snap action.

Another object of this invention, therefore, is to provide a switch of this type which has positive and reliable quick-make and quick-break action no matter how slowly the control shaft is operated; may be utilized for both single and multiple pole and throw; and may be operated by either angular or linear motion of a control member.

In accomplishing the foregoing objects, a spring contact having an insulator-striking block is moved from a normally biased position (either switch closed or open) to a controlled position (either switch open or closed) by the force of a spring-actuator engaging such block. The application of the force of the spring-actuator is controlled by the movement of such actuator relative to a fixed cam. As the actuator moves either into or out of juxtaposition with respect to such block the cam flexes the actuator out of its normal position so that upon release from the cam the actuator snaps either against or away from such block to quickly move the spring contact with a snap action. In one direction of travel of the actuator it will move over said cam and in the opposite direction of travel it will move under said cam to effect the desired quick application or quick withdrawal of actuating force. This principle of quickly applying and re-

2

moving a force to and from the spring contact may be utilized in various ways. The spring contact may carry one or a multiplicity of contacts. It may be biased either into or out of engagement with fixed contacts. It may be normally in contact with one set of contacts and biased into contact with another set of contacts. Thus a single or multiple pole or single and double throw switching action may be obtained. No matter how slowly the control member moves the actuator the release of the latter from the cam is always instantaneous and complete so that the stored force is suddenly applied or removed to provide a sure and dependable snap action break or make of switch contact. The length of engagement between cam and actuator is relatively short so that only a minimum movement of the actuator is required to effect switching action. The actuator may be carried by a movable element of the other control component, the fixed cam may be positioned on the housing of such component, and the fixed contacts and spring contacts mounted on the cover for such housing. Thus a relatively small number of parts is employed and such parts incorporated with the elements of the other control component to make a compact inexpensive unit. As any type of relative movement between cam and actuator will control such actuator the movement of the control member may be linear or angular thus making the switch applicable for use with a large variety of other components. However, a switch embodying these principles may be constructed and used as a separate individual unit.

35. The novel features which are considered characteristic of the invention are set forth with particularity in the appended claims. The invention itself, however, both as to its organization and its method of operation, together with additional objects and advantages thereof, will best be understood from the following description of a specific embodiment when read in connection with the accompanying drawings, in which:

40. Fig. 1 is a view partly in elevation and partly in cross section on the meandering section line 1—1 in Fig. 2 of a switch embodying the present invention incorporated with a variable resistor, the switch being shown in "off" position;

45. Fig. 2 is a sectional view taken on line 2—2 of Fig. 1;

50. Fig. 3 is an enlarged fragmentary, sectional view taken on line 3—3 of Fig. 2 showing the relative position of the follower, cam, and striker block with the switch in "off" position;

55. Fig. 4 is a view similar to Fig. 3 with such parts

in the position assumed as the switch is being actuated toward "on" position;

Fig. 5 is a view similar to Fig. 3 with such parts shown with the switch in "on" position;

Fig. 6 is a view similar to Fig. 3 with such parts shown as the switch is being actuated toward "off" position;

Fig. 7 is a top plan view of another modification of the switch embodying the present invention and operated by lineal movement of the control member; and

Fig. 8 is a view in side elevation of the switch viewed in Fig. 7.

In Figs. 1 to 6, inclusive, the switch embodying the present invention is combined with another control component such as a variable resistor. As the variable resistor is of well-known construction it will not be fully described herein. The switch and variable resistor are mounted in a metal shell or case 10 to which is secured a mounting bushing 12 rotatably carrying a control member or shaft 14. The variable resistor is adjusted by the rotation of such control member as it moves an insulated contact shoe 16 staked to the inner end thereof. The variable resistor has customary electrical terminals, one of which is indicated at 18. The contact shoe 16, together with the inner end of shaft 14, comprise the mounting support for a spring-actuator 20 staked on and rotatable with such shaft. A cam follower 22 carried by the spring-actuator 20 is biased thereby to a neutral position spaced laterally from the body of such spring-actuator. The follower 22 may thus be flexed to either side of its neutral position. The actuator is stiff enough so that the follower while in substantially neutral position will be able to assert enough force to counteract the inherent force in the spring contact. Because of the inherent characteristics of the variable resistor there is one portion of the total movement of the shaft 14 at which it is desirable to accomplish switching operation. A fixed cam 24 is stationed near such portion in the normal path of travel of the follower 22 to engage the follower and cooperate in effecting switch operation. The cam 24 may be made, as is shown in Figs. 1 and 2, by cutting and forming out a portion of the wall of the housing 10, or any other way of so fixedly positioning the cam in the path of the follower will be satisfactory. It is only essential that the follower be momentarily flexed from normal position and suddenly released so that the force so stored therein by such flexing can be utilized to open or close the switch contact. In the particular embodiment shown in Figs. 1 to 6, the cam 24 is sloped rearwardly and upwardly (as viewed in Fig. 1). As viewed in Figs. 3 to 6, inclusive, "up" is "down" on the sheet, "top" is "bottom" on the sheet, and vice versa, because such views were taken on a sectional view of Fig. 2 and Fig. 2 is an inverted view. Hence, as the follower 22 is moved angularly clockwise (as viewed in Fig. 2) from the switch "off" position shown in Fig. 2 it will strike against the top of the cam 24 and be flexed upwardly. When the follower 22 clears the upper edge of the cam 24 it will forcibly spring to its normal unflexed position. When the follower 22 is returned angularly counterclockwise it will engage the bottom of cam 24 and be flexed downwardly until it clears the lower edge of such cam. The follower will then again spring to its normal unflexed position.

The controlled movement of the follower 22 is

used to operate a spring contact 26 mounted within the casing 10 on a terminal 28. In this embodiment spring contact 26 is inherently biased toward engagement with a fixed contact 30 5 also mounted within the casing 10 by a terminal 32. However, the inherent force in the spring contact 26 is not sufficient to overcome the inherent stiffness in spring-actuator 20 and cause it to have any substantial movement from normal position. Operative engagement between the follower 22 and the spring contact 26 is accomplished through an insulating block 34 secured to the end of the spring contact 26 by suitable means. An example of such means consists of a portion 36 cut from the body of the spring contact 26 and bent toward the end of such spring contact so as to pass through an opening in the block 34. The end of such portion is clinched against the block to hold it in place, as shown.

20 The width (vertical dimension as viewed in Figs. 3 to 6) of the block 34 is sufficient so that when it is engaged by the follower 22 the spring contact 26 will be raised from engagement with fixed contact 30. This is the position shown in Figs. 1, 2, and 3. In order to permit the follower 22 to be flexed upwardly by the cam 24 without letting the spring-actuator 20 make contact with the fixed contact 30, a lower corner of the block 34 is cut off, as indicated at 38, to provide a sloping 25 edge substantially parallel with the surface of the cam 24. Thus as the follower 22 is moved clockwise, as viewed in Fig. 2, and engages on the top of cam 24, it will slide upwardly along the sloping surface 38 at the same rate that it slides upwardly along the cam 24. This relationship, as shown in Fig. 4, will not permit the block 34 to change its position until the follower 22 leaves the cam 24. When the follower leaves the cam 24 and springs to its normal position, the inherent resilience in the spring contact 26 30 will cause it to snap to the closed or "on" position of Fig. 5. The spring-actuator 20 is then free to move with the control member 14 as it regulates or operates the other component. Upon reverse movement of the member 14 the follower 22 will ride down the bottom of the cam 24 (see Fig. 6) and not contact the block 34 until it clears the end of such cam. At such time the follower will rise and strike the spring arm 22 breaking the contact with a snap.

50 In Figs. 7 and 8 there is shown a modification in which the switch embodying the present invention is not combined with any other control component. In this modification the switching action results from a lineal movement of the control member. The control member constitutes a push bar 40 which is slidably mounted in a pair of spaced brackets 44 and 46 carried by a frame 42. A leg 48 on such frame forms the support for an insulating plate 50 on which is mounted the switch contacts. The fixed contact 52 is carried on a bracket 54 so as to be spaced from the plate. A terminal 56 is secured to such bracket. The spring contact 58 is secured to the plate 50 and underlies the fixed contact 52 being biased so as to be normally in engagement therewith. A terminal 60 is connected with the spring contact 58. The spring contact 58 is snapped "open" in a manner similar to that previously described in connection with the first modification by the controlled action of a spring-actuator 62 mounted on the push bar 40. This spring-actuator has a cam follower 64 in lineal alignment with a fixed cam 66 carried on the frame 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

42. The spring contact 58 carries an insulating

block 68 with a sloping edge 70 substantially parallel to and slightly spaced from the cam 66 in the normal position as shown in Fig. 8. When the push bar 40 is moved in a lineal path inwardly or to the right as viewed in the figures, the follower 64 will ride up on the cam 66 and bias the spring-actuator 62 from its normal position. When the follower 64 clears the cam 66 the actuator 62 will cause it to spring down on the top of the block 68 and snap the contacts to "open" position. When in this position lineal movement of the push bar 40 to the left will cause the follower 64 to ride down the underside of cam 66. During such movement the follower will be in engagement with the sloping surface 70 and thus still keep the contacts open. However, when the follower 64 clears the cam 66 it will spring to its normal position shown in Fig. 8 permitting the contacts to snap closed.

The principle herein described of actuating single pole throw switches can also be used to operate multiple pole single throw switches or multiple pole double throw switches. The switches may be operated from either normally open to closed or normally closed to open positions. Any number of fixed contacts may be employed and engaged by a number of movable contacts operated by a single actuator. In the case of a double throw switch the fixed contacts are positioned on opposite sides of the spring contact member. In both the modifications disclosed herein, the follower, the fixed cam, and the insulating block all have sloping surfaces which are substantially parallel. The purpose of this is to provide smoother action. However, as previously explained, the essence of the invention is to momentarily force the spring-actuator out of a normal position. This may be done by a follower which is sloped and a fixed cam which is not sloped at all. The same result may be accomplished by a follower which has no slope and a cam which has the desired slope. It is not necessary in all cases to provide a sloping surface on the striker block except to provide necessary clearance to permit the spring contact to go to completely normally closed position. It does not make any difference in the desired switching action if the spring contact is moved farther away from "off" position during the return movement of the spring-actuator.

Although only several embodiments of the invention are shown and described herein, it will be understood that this application is intended to cover such other changes or modifications as come within the spirit of the invention or scope of the following claims.

I claim:

1. In an electric switch having relatively movable contacts, a flexible actuator having a normal path of travel in said path for engaging one of said contacts to control the movement of said contacts, and cam means in said path for flexing said actuator from said normal path, said actuator upon release from said cam means controlling the movement of said contacts with a snap action.

2. An electric switch as claimed in claim 1 in which said actuator rides up and snaps down from said cam means in one direction of travel and rides under and snaps up from said cam means in the opposite direction of travel to effectuate operation of said contacts.

3. In an electric switch having relatively movable contacts, one of said contacts having an actuator engaging portion, a spring actuator hav-

ing a normal path of travel in alignment with said portion, an actuator flexing member in said path, and camming means operative between said member and said actuator to temporarily flex said actuator out of said path and suddenly release said actuator for return to said path while in juxtaposition with said portion to operate said contacts.

4. An electric switch as claimed in claim 3 in which said portion and said camming means have related sloping surfaces permitting said actuator to be flexed while traveling from said portion toward said member without operating said contacts.

5. An electric switch including a spring contact biased toward one position, a relatively stiff member having a normal place in which said member holds said spring contact away from said one position, cam means for temporarily deflecting said member from said normal place and permitting said member to snap back to said normal place upon release of said cam means consisting of a flat sloped camming surface and a movable follower one of which is relatively fixed and the other of which is moved by a control member, and a control member for said cam means.

6. An electric switch including a spring contact biased toward one position, a relatively stiff member having a normal place in which said member holds said spring contact away from said one position, cam means for temporarily deflecting said member from said normal place and permitting said member to snap back to said normal place upon release of said cam means consisting of upper and lower flat sloped camming surfaces and a movable follower, one of said follower or said surfaces being relatively fixed and the other being movable by a control member, and a control member for said cam means, said follower riding up said upper surface in one direction of movement of said control member and riding down said lower surface in the opposite return direction of movement of said control member.

7. An electric switch as claimed in claim 5 in which said control member consists of a rotating shaft.

8. An electric switch as claimed in claim 5 in which said control member consists of a slidable bar.

9. An electric switch comprising relatively movable contacts, a rotating member movable in a normal path to actuate the contacts, a stationary obstruction in said path, said member riding over one side of said obstruction and being deflected from its normal path and snapping back to its normal path as it leaves said obstruction when operated in one direction, said member riding over the other side of the obstruction and being deflected in the opposite direction from its normal path and snapping back to its normal path as it leaves said obstruction when operated in the opposite direction, the "snap" in opposite directions as it passes alternate ends of said obstruction operating said contacts.

10. An electric switch having relatively movable contacts, an actuating member consisting of a flat spring, a flat cam in the path of said spring and set at an angle to said path so that said spring engages and rides over one side of the cam when it approaches it from one direction and engages and rides over the opposite side of the cam when it approaches from the opposite direction, departure from the cam at each end effecting movement of said switch contacts.

11. An electric switch having movable con-

tacts, a movable actuating member, a stationary cam for temporarily biasing said member, a striker block on one of said contacts having a portion beneath said cam engageable by said member as said member snaps off said cam in one direction of travel thereof to operate said contacts, said block having a taper along which said member slides in the return opposite direction of travel so that as said member is biased by said cam said block will not be moved sufficiently to operate said contacts until said member clears said cam.

JOHN S. COLDWELL.
